CLAIM

The ornamental design for a tactical flashlight, as shown and described.

DESCRIPTION

FIG. 1 is a front, right side, top perspective view of a tactical flashlight, showing my design.

FIG. 2 is a rear, left side, bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is an enlarged view of portion 9 shown in FIG. 1. The broken lines in the drawings depict portions of the tactical flashlight that form no part of the claimed design. The oblique line shading shown in the drawings indicates a transparent or translucent surface. The long dash-short dash broken lines depict areas of enlargement and form no part of the claimed design.
